PROTECTIVE COVER

Logan T. Dixon, Elizabethtown, Ky.

Application December 14, 1949, Serial No. 132,905

1 Claim. (Cl. 45—68)

1

The present invention relates to protective covers for use in connection with bottled gas installations used to supply heating and lighting in individual homes, and has particular reference to an improved and simplified form of cover device which may be employed readily with bottled gas installations of conventional type now in use, providing a maximum of protection against unauthorized tampering with the installation.

With homes where no community gas service is available, fuel gas is supplied to the individual home in bottles or metal containers, which must be replaced at regular intervals by the supplier. The bottled gas installation usually includes two containers and a gas metering valve, all positioned outside the home, with suitable conduits leading to the stove or lighting fixtures if desired, inside the home. Thus, the bottled gas installations are exposed to weather, as well as being exposed to tampering by unauthorized personnel. These installations present a fire hazard which has been the subject of civil regulation, to the effect that the containers, valve and conduit mechanisms leading from the containers must be suitably protected, in order to eliminate deterioration lending to dangers of fire and explosion incident to leakage of the gas from the containers. In many communities, the gas containers must be positively secured and the metering valve and other operating mechanism housed by covers, which must be positively secured in place. The use of locks to secure the covers has been suggested, as well as the provision of enclosing boxes provided with hinged covers or walls permitting or facilitating removal or replacement of the containers. These types of protective covers readily deteriorate through rusting of the locks, hinge mechanism or otherwise due to the constant exposure to the weather, also necessitating the frequent replacement and repair, with particular reference to painting and oiling of the mechanisms. Thus, the expense of upkeep of these protective devices is a substantial factor. Also, unless the protective covers are locked in place, they do not eliminate the dangers of tampering.

It is an object of the present invention to provide a protective cover device for use with bottled gas containers, meeting the requirements of safety regulations, and which may be constructed of inexpensive materials requiring little upkeep.

A further object is to provide a protective covering for bottled gas containers which may be readily installed with conventional container installations currently employed, without modification, and which provides positive protection against the elements, as well as unauthorized tampering with the container installation, as for example, by children.

2

A further object is to provide a protective cover for bottled gas containers which normally rests in protecting position over the gas metering valve and conduits leading from the containers to the home, and which may be removed from this position only by movement of the cover vertically from the container protecting position.

A further object is to provide a protective cover for bottled gas installations which may be secured to the bracket which normally supports the gas meter valve in such a manner that the cover can only be removed with an upward or vertical pressure evenly applied to maintain the cover in aligned position relative to the bracket any other lifting pressures incurring a partial lock between the cover and the supporting bracket, preventing removal of the cover.

A further object is to provide a protective cover which is free from openings capable of receiving and retaining water or snow, causing the cover to jam or freeze in place, and which when partially removed, will fall back into proper position once the removing pressure is released.

A further object is to provide a protective cover for bottled gas installations which may be constructed of inexpensive materials and easily assembled at a low cost per item requiring little upkeep.

Further objects and advantages of the present invention will be apparent from the following description taken in connection with the drawings, wherein:

Figure 1 is a perspective view of the protective cover of the invention installed in place over bottled gas container installations;

Figure 2 is a vertical cross-sectional view of the cover and support, including the bracket;

Figure 3 is a top view of the cover; and

Figure 4 is an enlarged view of a form of latch which may be employed to secure the cover in protective position.

In its broadest application, the invention comprises a protective cover to be positioned over fuel gas containers of conventional type, supported by a bracket having a projection engaging the cover whereby the cover may be removed from the projection only by impression of an upward pressure, evenly distributed on the cover, moving the cover vertically and upwardly in exact alignment with the bracket projection. The bracket engaging means within the protective cover is positioned so as to prevent the accumulation of water and ice therein which would prevent normal operation of the cover in winter or incurs rusting of the mechanism. The engagement of the cover and supporting bracket provides a partial lock, which is effective in preventing removal of the cover permitting tampering with the gas container installation by unauthorized personnel, with particular reference to children. The par-

tial lock becomes effective when an upward pressure is exerted on the cover of any one side, biasing the cover support means and the means on the cover engaging the support in such a way as to prevent removal of the cover. It will be readily apparent that with children, lifting for example the front edge of the cover or one of the sides will thus jam the cover supporting mechanism, preventing removal, but in no way damaging the cover for removal by proper personnel. If the child is successful in moving the cover upwardly an inch or more, upon release of pressure the cover will fall back into proper position, protecting the containers.

Referring now to the drawings, there is shown in Figure 1 a perspective view of the cover 10 mounted upon a bracket referred to generally as 11. The valve assembly and conduits of the gas containers are shown in dotted line 12 as being mounted upon the bracket 11, showing the relative positioning of the parts when the protective cover is assembled in position thereover. A conventional type of fuel gas bottle 13 is also shown.

The protective cover 10 comprises a member having a top 14, a front panel 15 dropping perpendicularly from the top, and side walls 16 having portions 17 tapering inwardly and rearwardly to a back plate 18, adapted to rest next to the building or other structure to which the container assembly is secured.

The bracket 11 consists of a plate 19 secured to a wall or other structure not shown by screws 20. The plate 19 may have raised portion 21 centrally and extending vertically of the bracket for mounting the container valve mechanism. The bracket 11 is provided with a vertical extension or arm 22 secured thereto preferably setting within the raised portion 21 by welding or otherwise, the extension 22 having an offset portion 23 for purposes of spacing the extension from the wall to facilitate removal and replacement of the protective cover 10.

The rear wall 18 of protective cover 10 is provided with an arm securing number or sleeve 24 formed of a raised portion 25 adapted to receive the arm 22 in slidable relationship therewith. The sleeve 24 extends vertically of the wall 18, preferably the entire length thereof to increase the area of contact between the arm 22 and the sleeve. In order to secure the protective cover firmly with regard to the bracket, it is preferred that the arm 22 and sleeve 24 be formed in close fitting relationship, permitting relative vertical movement between the cover and the bracket when a lifting pressure is properly applied, for example, by grasping the sides of the cover, and lifting evenly, but biasing and jamming upon movement of the protective cover with anything except a pressure along the vertical axis of the arm 22.

It will be further observed that the front panel 15 of the protective cover is adapted to rest at its lower edge upon the shoulders of the gas containers, thereby further supporting the weight of the cover when placed in its properly assembled position.

As shown in Figure 4, where a positive interlock between the arm 22 and the cover is desired, an aperture 26 is formed in the arm 22 adapted to receive a plug 27 mounted on a spring 28 and positioned by a cover plate 29. The lock assembly may be secured to the wall 18 so as to extend

within the sleeve 24 and engage the aperture 26 when the arm 22 is fully inserted within the sleeve. The tip of the plug 27 should be beveled so as to attain a snap lock action which may be established or broken by an increase in the pressure put on the cover, in a cover mounting or removing operation. With the combination of the spring lock and the binding action of the arm 22 and sleeve 24 when the cover is tilted, it is impossible to remove the cover with an improper application of cover removing pressures.

It will thus be observed that the present invention provides a protective cover mechanism for bottle gas containers which may be of simple construction yet which provides a positive protection to the container against unauthorized tampering, as well as from the elements. The container cover may be constructed of any desired material such as plastic and the like, preferred materials comprising metal such as aluminum and steel which are readily available and which may be painted if desired. Note that if the person tampering with the cover succeeds in effecting a partial removal thereof from the arm 22, on release of lifting pressure the cover will slide down on the arm 22 to its normal position.

While the invention has been described with reference to the specific structures shown, it is apparent that the general contour and shape of the protective cover may be modified from that shown without departing from the spirit of the invention. Similarly, more than one mounting arm 22 may be employed. If a more firm support for the protective cover 10 is desired, the provision of one such arm 22 is adequate for most purposes.

It is intended that the invention be limited only as described in the appended claim.

I claim:

A protective device for use in connection with bottled fuel gas containers, comprising a flat plate having a vertical, central, forwardly raised portion presenting a channel open at the rear face of the plate, said plate being adapted to be attached to a vertical surface, a solid, vertical, rod-like arm having a lower end portion seated in the upper end of said channel of said plate and secured therein and having an upper portion extending above the upper end of the plate and having an off-set adjacent the upper end of the plate spacing the upper portion of the arm forwardly of its lower portion and of said plate, a cover having back, front, side walls and a top, a sleeve secured against the inside of the back wall of the cover and extending substantially the depth of the back wall, said upper portion of said arm being slidably seated in said sleeve with a snug fit whereby said sleeve and arm bind to lock the cover to the arm when non-vertical upward pressure is exerted on the cover.
